UNITED STATES PATENT OFFICE

GEORGE S. CROWN, OF BAKERSFIELD, CALIFORNIA

INSECT TRAP

Application filed December 30, 1930. Serial No. 505,631.

This invention aims to provide novel means for catching flies and other insects that are either within or without a room, and, specifically to catch flies or other insects which may crawl up the outside of a screen door or up the inside of a screen door.

It is within the province of the disclosure to improve generally and to enhance the utility of devices of that type to which the invention appertains.

With the above and other objects in view, which will appear as the description proceeds, the invention resides in the combination and arrangement of parts and in the design of construction hereinafter described and claimed, it being understood that changes in the precise embodiment of the invention herein disclosed, may be made within the scope of what is claimed, without departing from the spirit of the invention.

In the accompanying drawings:

Figure 1 shows, in vertical section, a portion of a building equipped with the device forming the subject matter of this application;

Figure 2 is a horizontal section on the line 2-2 of Figure 6;

Figure 3 is a vertical section on the line 3-3 of Figure 2;

Figure 4 is a vertical section on the line 4-4 of Figure 2;

Figure 5 is an elevation showing a portion of a screen door equipped with the device forming the subject matter of this application;

Figure 6 is a vertical section taken through the trap, the door appearing in elevation.

In Figure 1, the numeral 1 marks the wall of a building, the ceiling of a room appearing at 2, and a porch roof at 3. The transom above the door 4 is designated by the numeral 7. An electric lamp 5 may be placed on the ceiling 2 adjacent to the door 4, and an electric lamp 6 may be placed on the porch roof 3, adjacent to the door, although, if there is sufficient light, one or both of the lamps 5 and 6 may be dispensed with, or put out. The screen body of the door is designated by the numeral 8.

A guide plate 9 is held apart from the

frame of the door 4, on the inside of the door, but is connected to the frame of the door by a top spacer 10 and by end spacers 11. The construction is such, that, at the lower end of the guide plate 9, there is an entrance opening for insects, which crawl up the inside of the screen body 8 of the door, the entrance opening being marked by the numeral 12 in Figure 4.

The trap embodies a box-like casing, denoted as a whole by the numeral 14. The body of the casing 14 comprises a metal back plate 15, metal end plates 16, a screen top 17, a screen front 18, and a bottom plate 19 having holes 20.

The holes 20 normally are closed by a bottom closure 21, connected by hinges 22 with the back plate 15 and held closed by pivoted latches 23 (of any desired construction) mounted on the end plates 16 of the casing.

Angle brackets 24 are attached to the end plates 16 of the trap casing, as shown in Figure 4, these angle brackets being screwed to the outer surface of the door 4, as disclosed in Figure 5. The casing of the trap is attached additionally, to the door, because the back plate 15 has depending tongues 25 (Figures 5 and 6) connected by bolts 26 with a strip 27, the bolts 26 passing through the screen body 8 of the door 4, the strip 27 and the tongues 25 being located on opposite sides of the screen body 8, as Figure 4 will show.

Main triangular leaders 28, made of wire netting, are secured to the bottom plate 19 of the trap casing, and are spaced apart longitudinally of the casing, as Figure 6 will show. These leaders 28 do not open downwardly through the casing 14, because their lower ends are closed by the bottom plate 19. Each of the leaders 28 has a reduced neck 29 at its upper end. The leaders 28 are connected to flanges 30 (Figures 4 and 6) which project inwardly from the back plate 15 of the trap. The flanges 30 form, in the back plate 15 of the trap, triangular openings which communicate with the leaders 28, at the back of the leaders. The aforesaid openings register with openings 31 (Figure 4) in the screen body 8 of the door 4. They register, also, with correspondingly shaped openings

32 in a filler 33 secured between the guide plate 9 and the screen 8 of the door 4.

On the downwardly opening closure 21 for the casing 14 are located tapered leaders 34. The tapered leaders 34 open downwardly through the closure 19. When the closure 21 is shut on its hinges 22, the tapered secondary leaders 34 are disposed within the casing 14, between the main leaders 28, as shown in Figures 6 and 4. The secondary leaders 34, unlike the main leaders 28, do not open backwardly through the rear plate 15 of the casing 14, but open upwardly into the casing through the tapered necks 35 at the upper end of the leaders 34. The lower ends of the secondary leaders 34 are mounted on inclined flanges 36, carried by the bottom closure 21, to be seen in Figures 6 and 3 of the drawings, and when the member 21 is closed, the leaders 34 stick up through holes in the bottom-proper 19 of the casing 14.

In practical operation, referring to Figure 3, the flies on the outside of the screen 8 move upwardly as indicated by the arrow A in Figure 3 and enter the secondary leaders 34, the flies passing through the necks 35 of the leaders 34 into the casing 14.

Referring to Figure 4, it will be seen that the flies on the inside of the door move upwardly along the screen 8, as indicated by the arrow B and pass through the opening 12, in front of the guide plate 9, the flies passing thence through the openings 32 of the filler 33, and through the openings 31 of the screen 8, into the main leaders 28, the flies passing out of the leaders 28, into the casing 14, of the trap, through the necks 29 of the leaders 28.

The construction is such that the trap, although located on one side of the door will catch flies which are on either side of the door.

The transom 7 will afford the necessary light from the lamp 5, and the lamp 6, being located above the casing 14, will afford the necessary light, also.

If, owing to conditions of daylight, or other conditions, the lamps 6 and 5 are unnecessary, one or both of them, of course, can be extinguished.

50 The operator moves the latches 23 outwardly, thus setting the hinged bottom closure 21 free, so that it can be swung downwardly. When the bottom closure 21 is swung downwardly, the secondary leaders 34 are carried downwardly also. This opens the holes in the bottom-proper 19, which are occupied by the secondary leaders 34, when the closure 21 is shut, as in Figures 6 and 3. Through the openings thus provided, the dead flies can be 55 brushed out, but in order to brush out the flies conveniently from in front of the main leaders 28, the openings 20 are provided.

If the operator wishes, he can put any kind of bait in the casing 14, but since a patent will 60 not be granted on a fly trap characterized by

any specific bait support, the operator has been left free to support the bait in any way that he wishes.

Having thus described the invention, what is claimed is:

1. A trap of the class described, comprising a casing provided with a leader which opens through the side of the trap, the trap including a bottom having an opening, a closure hinged to the trap and cooperating with the bottom of the trap, and a leader carried by the closure and occupying the opening when the closure is shut, the closure carrying the last-specified leader clear of the opening, when the closure is opened, thereby to leave the opening unencumbered. 70 75 80

2. A trap of the class described, comprising a casing provided with a leader which opens through one side of the casing, the casing being provided with a bottom and the bottom having holes, a hinged closure for one of the holes, and a leader carried by the closure and opening through the closure, the last-specified leader occupying the other hole when the closure is shut. 85 90

3. A trap of the class described, comprising a casing provided in its bottom with holes, a closure hinged to the casing, and a leader carried by the closure and opening through the closure, the leader occupying one of the 95 holes when the closure is shut, and the closure covering the other hole when the closure is shut.

In testimony that I claim the foregoing as my own, I have hereunto affixed my signature. 100

GEORGE S. CROWN.
